UNITED STATES PATENT OFFICE

WILLIAM T. FERGUSON, OF BECKLEY, OF WEST VIRGINIA, ASSIGNOR OF TWO-THIRDS
TO EDGAR M. CROUCH AND HERMAN J. THORNE, BOTH OF BECKLEY, WEST VIRGINIA,
AND ONE-THIRD TO D. E. LLOYD, TRUSTEE

RAILROAD CROSSING GATE

Application filed April 15, 1930. Serial No. 444,572.

This invention relates to crossing gates for railways on which, electric, steam, gas or other form of propelled trains travel, and one feature of the invention is the provision of suitable housings adjacent the intersection of a roadway and railway, on which are mounted suitable gates adapted to be disposed across the roadway or elevated to inoperative position.

10 A further feature of the invention is the provision of means mounted within the housings for raising or lowering the gates automatically.

15 A further feature of the invention is the provision of means for so mounting said gates that when in lowered position, they will swing laterally when struck by an approaching road vehicle without causing injury to the vehicle or gate.

20 A further feature of the invention is the provision of means for automatically returning the gates to position across the roadway should the gates be swung laterally from any cause, when in lowered position.

25 A further feature of the invention is the provision of a suitable turn table for the dome portion of the housing.

Other objects and advantages will be hereinafter more fully set forth and pointed out 30 in the accompanying specification.

In the accompanying drawings which are made a part of this application,

Figure 1 is a diagrammatic view of highway and railway in crossing relation, with 35 parts shown in full lines in operative position and in other positions by dotted lines.

Figure 2 is a side elevation of a gate and its supporting housing, with the gate in lowered position in full lines and in elevated 40 position by dotted lines.

Figure 3 is a horizontal sectional view, as seen along line 3—3, Fig. 4, with the gate lowered.

45 Figure 4 is a vertical sectional view, as seen along line 4—4 of Fig. 3, and shows the gate in elevated position.

Figure 5 is an enlarged detail sectional view, showing the bearing means between the dome and housing.

50 Figure 6 is an elevational view thereof.

Figure 7 is a vertical sectional view through the gate operating means, and,

Figure 8 is a sectional view thereof as seen along line 8—8, Figure 7.

Referring to the drawings in which similar reference numerals designate corresponding parts throughout the several views, the numeral 1 designates a railway track and 2 indicates a vehicle roadway, which crosses the railway track and while I have shown but a single trackway, it will be understood that two or more trackways may be laid, side by side, and that the trackway is shown as electrically equipped, yet other forms of traction means may be employed for propelling the trains over the trackways. It will likewise be seen that although but a single gate structure is shown on opposite sides of the railway, these gates may be arranged in multiples, as desired.

In order to warn any one traveling the roadway that a train is approaching the crossing, gates 3 are positioned on opposite sides of the railway tracks 1, at a suitable distance therefrom, each gate being pivotally mounted on a shaft 4 extending transversely through the dome 5 of a housing 6, so that said gate may be swung downwardly to dispose the major portion of the gate 70 across the roadway and in the path of an approaching vehicle or a pedestrian. The gates 3 are, in the examples shown, bifurcated at their pivoted ends, the beam portions 7 of each gate being in straddled relation to the dome 5, so that the beams of the gate are fixed to the opposite ends of the shaft 4.

The housing 6 is hollow and preferably cylindrical in cross section, the lower edge thereof having a lateral flange 8, which may be attached to a concrete or other form of base 9, in any suitable manner, as by means of bolts 10. The upper edge of the housing 6 is preferably thickened inwardly to form a broad base 11, on which are mounted any suitable form of bearing rollers 12, which receive and form a bearing for the dome 5, the lower edge of the dome having 100

a bearing surface 13 over which the rollers travel.

Vertically disposed within the housing 6 is the standard electrically operated oil cylinder 14. The lower end of said cylinder is pivotally secured to the foundation 9 or base structure of the apparatus by means of the eyebolt means 15, the piston rod 16 extending from the upper or motor end of the cylinder to the U crank 17 both ends of which are integrally secured to the gate shaft 4. Said oil operated cylinder, as before indicated, is of standard commercial design, and in the example shown has a motor 18 at the upper end, the oil cylinder proper 19 being at the lower end.

Adjacent the roadway, a circuit breaker 20 is embodied with the conventional trolley wire 21, and is adapted to be operated by the trolley wheel of the passing electric train (not shown). Some distance along the trolley 21, from the roadway 2, are disposed the electric contact makers 22 and 23 one on each side of said roadway, and are also operated by the passing trolley wheel. Said contact makers serve to operate the motors 18 of the oil cylinders 19 thru the relay apparatus 24 as will be understood.

By this arrangement it will be understood that an electric train approaching the roadway 2 from either side will actuate one of the electric contact makers 22 which causes current to be immediately carried to the motors 18 causing the impellers 25 to be rotated, the oil or the like within the cylinders 19 being forced throughout the slots in the impellers thus elevating the impellers and causing the piston rods 16 to direct upward force against the U type cranks 17 which rotate the gates 3 thru their shafts 4 to closed, or lowered position, as shown in Fig. 1. As the train reaches the proximity of the roadway, 2, it strikes the circuit breaker 20 and the operation of the oil cylinders 19 being thus discontinued, by cutting out the motors 18, the counterweights 26 of the gates serve to swing same upwardly to an open position, as indicated by dotted lines in Fig. 2.

If coincident to the passing of a train, a traveller on the roadway 2 should be unable to bring his vehicle to a stop before reaching the gates 3, and it is found necessary to strike same, said gates by the force of this contact swing around to a position indicated by the dotted lines 27, Fig. 1, the dome 5 being correspondingly rotated on the rollers 12. If on the other hand the traveller should find himself between the gates after they are closed he may crowd his vehicle against either gate, thus swinging same into a position indicated by dotted lines 28. As the cylinder structure 14 is pivotally connected with the base or foundation 9 and as the upper end of the piston rod 16 connects with

the crank 17, the piston rod must have sliding connection with the crank 17 and the curvature of said crank, when the gate is in lowered position, must be radial to the pivotal axis of the dome 5 so that the dome 70 and parts carried thereby may be rotated without affecting the piston rod 16 and parts associated therewith.

In order that the gates may be immediately righted after being freed from the interfering vehicle, a trunnion 29 extends downwardly from the inwardly extending web 30 of the dome 5 at a medial of said dome, thru a corresponding web 32 of the housing 6. Said trunnion extends downwardly beyond 80 the web 32 and carries the crank 33, which is adapted to be swung about within the housing 6 when the dome 5 is rotated. The cable 34 extends downwardly thru the free end of said crank, the upper protruding 85 end being held by retaining clamp 35. The weight 36 is attached to the lower end of said cable. The sheave wheels 37 are mounted by the bracket 38 of the housing 6, so as to straddle said cable, one being on each side of the vertical plane of said crank. When the gates 3 are struck by a vehicle as described above, the crank 33 correspondingly rotates running the cable 34 up over one of the sheave wheels 37 thus raising the 90 weight 36. It will therefore be understood that as soon as the gates are again free, the weight 36 will draw the end of the crank 33 back to its normal position, the cable 34 being drawn back over the same one of the 95 pulleys 37, in opposite directions.

The hole 39 thru which the cable 34 is disposed thru the crank 33, has a gradual bell-mouth lower termination 40 which prevents the cable 34 from being easily severed at 105 this point thru ordinary use. Slightly toward the main part of each of the gates 3 beyond the shaft 4, a loop 41 is attached at one end to each of a pair of the beams 7, said loop being adapted to somewhat straddle the dome 5 when the gate is in closed position as shown in Fig. 2 and restrict the downward movement of the gate by contact with the stop lug 42 of the respective domes 5.

The relay 24 is of standard commercial design preferably and now in common use. The conductors 43 communicate the circuit makers 22 and 23, and the circuit breaker 20 with said relay apparatus, and conductors 44 feed the motors 18 from the relay juncture 45, return conductors 46 being grounded through said relay apparatus by means of the conductor 47 to one of the 110 rails 1.

A bell type danger gong 48 is mounted on the post 49 adjacent the intersection of the roadway 22 and the rails 1, and concurrently with the operation of the motors 18, said 115

gong is actuated by the conductor 50 and the ground connection 51.

5 A stop signal light 52 also conveniently mounted on the post 49 over said gong, is likewise actuated by the conductor 53 through the relay apparatus 24, the conductor 54 serving as a ground connection for same.

10 While the description and drawings illustrate in a general way certain instrumentalities which may be employed in carrying the invention into effect, it is evident that many modifications may be made in the various details without departing from the scope 15 of the appended claims, it being understood that the invention is not restricted to the particular examples herein described.

What I claim is:

1. In a crossing gate, a hollow housing, a 20 base for said housing, a dome rotatably mounted on said housing, a shaft extending through said dome, a gate structure attached to said shaft, a substantially U-shaped crank attached to said shaft, and an electrically 25 operated impeller pivotally mounted on said base within said housing for controlling the raising and lowering of said gate said impeller having sliding connection with said U-shaped crank whereby said crank may 30 slide transversely through said connection when the dome is rotated.

2. In a crossing gate, a housing, a dome rotatably mounted on said housing, a gate carried by said dome and adapted to swing 35 laterally when in lowered position and rotate the dome, a crank adapted to swing in an arc of a circle when the dome is rotated, said crank having an opening therethrough, a cable passing through said opening, the lower extremity of said opening being flared 40 to prevent wear on said cable, a weight attached to said cable, and sheaves over which said cable travels for causing the weight to elevate when the dome is rotated and return the gate to initial position when lateral 45 pressure is relieved therefrom.

3. In a crossing gate, a housing, a dome mounted thereover, rollers mounted on the housing for receiving the weight of said dome, a shaft extending transversely 50 through said dome, a gate structure mounted on said shaft, an electrically operated impeller mounted in said housing and pivotally secured to the base of the housing, a substantially 55 U-shaped crank attached to said shaft, and a piston rod extending from said impeller and having sliding engagement with said crank, whereby said gate may swing laterally in either direction when in lowered position incident to lateral impact thereagainst without affecting said piston rod.

In testimony whereof, I have hereunto set my hand on this the 8th day of March, 1930.
